(57) **CLAIM**

The ornamental design for a sensor cover package, as shown and described.

DESCRIPTION

FIG. 1 is a top plan view of a first sensor cover package, showing my new design;

FIG. 2 is a right side elevational view thereof;

FIG. 3 is a back elevational view thereof;

FIG. 4 is a left side elevational view thereof;

FIG. 5 is a bottom plan view thereof;

FIG. 6 is a front elevational view thereof;

FIG. 7 is a perspective view of thereof;

FIG. 8 is a top plan view of a second sensor cover package, showing my new design;

FIG. 9 is a right side elevational view thereof;

FIG. 10 is a back elevational view thereof;

FIG. 11 is a left side elevational view thereof;

FIG. 12 is a bottom plan view thereof;

FIG. 13 is a front elevational view thereof;

FIG. 14 is a perspective view of thereof;

FIG. 15 is a top plan view of a third sensor cover package, showing my new design;

FIG. 16 is a right side elevational view thereof;

FIG. 17 is a back elevational view thereof;

FIG. 18 is a left side elevational view thereof;

FIG. 19 is a bottom plan view thereof;

(Continued)

FIG. 20 is a front elevational view thereof;
FIG. 21 is a perspective view of thereof;

FIG. 22 is a top plan view of a fourth sensor cover package, showing my new design; the right side elevational view, the back elevational view, the left side elevational view, the bottom plan view, and the front elevational view are the same as those of the first sensor cover package shown in FIGS. 2-6;

FIG. 23 is a top plan view a fifth sensor cover package, showing my new design, the right side elevational view, the back elevational view, the left side elevational view, the bottom plan view, and the front elevational view are the same as those of the first sensor cover package shown in FIGS. 2-6;

FIG. 24 is a top plan view a sixth sensor cover package, showing my new design, the right side elevational view, the back elevational view, the left side elevational view, the bottom plan view, and the front elevational view are the same as those of the first sensor cover package shown in FIGS. 2-6;

FIG. 25 is a top plan view a seventh sensor cover package, showing my new design, the right side elevational view, the back elevational view, the left side elevational view, the bottom plan view, and the front elevational view are the same as those of the first sensor cover package shown in FIGS. 2-6;

FIG. 26 is a top plan view a ninth sensor cover package, showing my new design, the right side elevational view, the

back elevational view, the left side elevational view, the bottom plan view, and the front elevational view are the same as those of the third sensor cover package shown in FIGS. 16-20;

FIG. 27 is a top plan view a tenth sensor cover package, showing my new design, the right side elevational view, the back elevational view, the left side elevational view, the bottom plan view, and the front elevational view are the same as those of the third sensor cover package shown in FIGS. 16-20;

FIG. 28 is a top plan view an eleventh sensor cover package, showing my new design, the right side elevational view, the back elevational view, the left side elevational view, the bottom plan view, and the front elevational view are the same as those of the third sensor cover package shown in FIGS. 16-20; and,

FIG. 29 is a top plan view a twelfth sensor cover package, showing my new design, the right side elevational view, the back elevational view, the left side elevational view, the bottom plan view, and the front elevational view are the same as those of the third sensor cover package shown in FIGS. 16-20.

The broken lines in the drawings are used to illustrate unclaimed environmental structure and form no part of the claimed design.
